AUTOMATICALLY-THREADING LOOM SHUTTLE

Application filed February 2, 1929. Serial No. 336,937.

This invention relates to automatically threading loom shuttles and is more particularly directed to the thread tensioning means.

In automatic filling replenishing looms the thread ends of the full bobbins or filling carriers in the hopper are usually secured to a fixed point, so that on replenishment of filling the shuttle will be partially threaded on the first pick of the shuttle. Unless the thread is properly tensioned on the first pick of the shuttle following replenishment it will not be properly laid in the shed, a condition which may frequently be observed in the finished cloth, and much thought and inventive ingenuity have been exercised in automatic threading shuttles to provide tension on the thread on the first pick of the shuttle. On the second pick of the shuttle following replenishment it has been suggested heretofore that an additional tensioning device may act upon the thread, the result being that the tension exerted on the thread during the first pick of the shuttle will differ materially from the tension exerted on the thread during subsequent weaving when the shuttle is fully threaded.

One of the purposes of the present invention is to provide an automatically threading loom shuttle with thread tension means to apply suitable tension on the thread during the first pick of the shuttle and a substantially similar or equal tension upon the thread during subsequent weaving when the shuttle is fully threaded.

In accordance with the present invention, the automatically threading shuttle is provided with a scroll of novel construction which will deflect and tension the thread on the first pick of the shuttle following replenishment, and when the thread leads from the side delivery eye on the second and subsequent picks of the shuttle the tensioning effect of the scroll is partially or wholly relieved 45 from the thread and the latter is passed into

control of other tensioning means which remains active to tension the thread during normal weaving operations.

The invention and novel features thereof will best be made clear from the following description and the accompanying drawings of one good form thereof.

In the drawings:

Fig. 1 is a plan view of an automatically threading shuttle provided with the present invention, and showing the relation of parts on the first pick of the shuttle following replenishment;

Fig. 2 is a perspective view showing the relation of parts when the shuttle is fully threaded and the thread leads from the side delivery eye;

Fig. 3 is a section on the line 3—3 of Fig. 2;

Fig. 4 is a longitudinal section of the front end of the shuttle containing the present invention on the line 4—4 of Fig. 3; and

Fig. 5 is a detail showing a slightly modified form of scroll.

The shuttle 1 has the usual bobbin chamber 2 and forward of the bobbin chamber is 70 the longitudinal thread passage 3 which communicates with the side delivery eye 4.

In the illustrated form of the invention, the shuttle is provided with a threading block 5 which may be formed with a longitudinal thread passage 3, and at one side of the threading block is the thread director 6 having its front edge portion 7 slightly separated from the shuttle body, at 8, to form a passageway 9 between the edge of the thread director and the shuttle wood, through which the thread may pass on the second pick of the shuttle following replenishment. The end portion of the thread director 6, as shown, underlies the guard 10, and the parts thus described may be of any usual construction.

Mounted in the longitudinal thread passage 3 is a scroll which, on the first pick of the shuttle following replenishment, takes 90

control of the thread *a* and by deflecting the thread about parts of the scroll exerts sufficient tension on the thread to insure its being properly laid in the shed. The coils or loops of the scroll may be multiplied at pleasure 5 and obviously the tension upon the thread increases or diminishes by variations in the distance between the members of the scroll, and indeed the members of the scroll may be brought sufficiently near to each other to exercise a deterrent effect upon the passage of any loops of filling or "slugs" through the shuttle eye and into the cloth.

As shown more particularly in Figs. 1 to 15 4, inclusive, the scroll is formed of wire or other suitable material and its end portions are fastened at opposite sides of the thread passage, and between the end portions of the scroll is a loop 11 which extends in a curved 20 path transversely of the thread passage.

In the present instance of the invention, the leg portions 12 and 13 of the scroll may be secured to the opposite walls forming the thread passage by providing the opposite 25 walls with suitable recesses into which the end portions 14 and 15 of the scroll may extend to thereby hold the scroll in proper position in the thread passage and cause the thread as it swirls during its withdrawal 30 from the filling carrier or bobbin on the first pick of the shuttle following replenishment to be guided about the loop portion 11 of the scroll into engagement over and under the leg portions 12 and 13 of the scroll, with the 35 result that the thread *a*, as indicated in Fig. 1, is deflected over and under the leg portions of the scroll and thereby has imparted to it the requisite tension.

As indicated in Figs. 1 and 2, the scroll may 40 be of double form, that is, the scroll adjacent the bobbin chamber may be duplicated at a point more remote from the bobbin chamber, and in such case the loop portion 16 of the duplicate scroll may occupy a position between the end leg portions 17 and 18 of the duplicate scroll. The ends of the duplicate scroll may 45 be secured at opposite sides of the thread passage in a manner similar to that already described for the companion scroll, and where 50 a duplicate scroll is employed it will be obvious that the thread *a* will be deflected between the end leg portions of each of the scroll members to thereby exert increased tension upon the thread where duplicate scrolls 55 are employed.

Where the scroll is formed in duplicate, as last described, the two companion scrolls may be formed of a single wire or other suitable material, but in either event each constitutes a scroll in itself. This formation of the 60 duplicate scroll is shown more particularly in Figs. 1 and 2 wherein the joining portions of the two scrolls enter a recess 19 at one side of the longitudinal passage.

65 The modification of the scroll, as indicated

in Fig. 5, is substantially the same as one of the duplicate scrolls, that is to say, the end portions 20 and 21 of the scroll of Fig. 5 may be appropriately secured, one at each side of the longitudinal thread passage, and between the end portions of the scroll the scroll loop 22 extends in a curved path transversely of the thread passage, the construction being such that when the swirling thread is engaged with the loop 22 it will be directed thereby over and under the end portions of the scroll, as at 23 and 24, and be suitably deflected to impart tension thereto on the first pick of the shuttle following replenishment.

Whether the scroll be of the duplicate type, as shown in Figs. 1 and 2, or of the single scroll type, as shown in Fig. 5, the swirling thread will be directed about the loop portion of the scroll so that it will occupy a position at one side of the longitudinal axis of the scroll without passing through the loops of the scroll. From the construction thus far described it will be apparent that where the scroll has its end portions secured at opposite sides of the longitudinal thread passage, the thread will not only be deflected and tensioned by passing over and under the end members of the scroll but will be located at one side of the longitudinal axis of the scroll on the first pick of the shuttle following replenishment, and since the swirling action of the thread contributes to its engagement in the condition above described, that part of the end member of the scroll under which the thread passes, as at 13, Fig. 1, and 24, Fig. 5, will act as a swirl arrester, so that as the thread is withdrawn from the shuttle on the first pick of the shuttle following replenishment, and swirling action of the thread after engagement by the scroll will take place from the scroll back into the bobbin chamber.

The character or detail structure of the scroll itself may be variously contrived, the essentials in this respect being that regardless of the particular structure, the end portions of the scroll shall be secured at opposite sides of the longitudinal thread passage.

When the shuttle has completed its first pick following replenishment and has returned to the replenishing side of the loom, the shuttle will become fully threaded, that is to say, the thread will be directed by the thread director to the side delivery eye where it will remain on second and subsequent picks of the shuttle during weaving. At such time it is desirable that the tension exerted by the scroll shall be partially or wholly removed and that a working tension device be employed for imparting to the thread a working tension during weaving.

Mounted in the threading block, in the present instance of the invention, is a thread deflector 25 which extends in an inclined direction towards that side of the thread passage opposite the thread engaging portion

of the scroll, as indicated in Fig. 1, with the result that when the thread is engaged by the thread deflector it will be carried laterally of the scroll from the scroll engaging portions, so that the scroll tension on the thread previously exerted will thereupon be partially or wholly removed.

The thread deflector 25 has the end portion 26 thereof secured to the thread director 6, preferably near the end portion thereof, as shown, and extends downwardly and backwardly, and has its lower end 27 secured in the threading block at the side of the thread passage opposite the delivery eye. By this construction it will be noted that when the thread passes to the side delivery eye through the passage 9 it will engage about the thread deflector 25 and consequently be deflected laterally of the thread passage.

Cooperating with the thread deflector 25 is a resilient thread tensioning means for exerting tension upon the thread upon the second and subsequent picks of the shuttle following replenishment by deflecting the thread relative to the thread deflector.

The resilient member may be variously contrived but as shown in the present instance of the invention consists of a bow spring 28, the lower end portion 29 of which is secured to the threading block at the side of the thread passage opposite the delivery eye 4, and at this point the bow spring 28 extends forwardly with its bowed end 30 seated in a recess 31 of the shuttle wood, so that the thread may not engage beneath the bow spring. The upper portion 32 of the bow spring extends rearwardly from the bow 30 and its rear end portion at 33 projects into an elongated slot 34 formed in the threading block at the side of the thread passage opposite the side delivery eye, with the result that when the shuttle is fully threaded on the second pick following replenishment it will pass about the thread deflector 25 and over the upper member 32 of the bow spring 28, and owing to the spring action of the resilient tensioning member the thread leading about the thread deflector 25 will be bent more or less to exert a weaving tension upon the thread, during subsequent picks of the shuttle, as indicated in Figs. 2 and 4. At the same time it will be obvious that owing to the deflection of the thread by the thread deflector 25 it will be relieved wholly or in part from the tension of the scroll, as indicated in Figs. 2 and 4; that is, the thread will be drawn from its scroll engaging and tensioning position at one side of the thread passage, Fig. 1, towards the longitudinal axis of the passage and thus relieved in whole or in part from the scroll tension, as indicated in Figs. 2 and 4.

From the construction described as one good practical form of the present invention it will be noted that on the first pick of the

shuttle following replenishment the scroll, which has its end portions secured at opposite sides of the thread passage, will exert tension upon the thread that it may be properly laid in the shed, and on following and subsequent picks of the shuttle when the thread leads from the side delivery eye the tension exerted by the scroll will be wholly or partially removed and working tension applied to the thread by the cooperating action of the thread deflector and the resilient member or bow spring.

The term "scroll" as herein employed is used in a general or broad sense to signify an element having convolute portions, turns or spirals which serve to guide or direct the swirling thread as the shuttle is picked.

What is claimed is:

1. An automatically threading loom shuttle having a longitudinal thread passage and side delivery eye, a scroll mounted in the longitudinal thread passage and having its ends secured at opposite sides of the thread passage that the thread may be deflected and tensioned by passing over and under the terminal portions of the scroll in the longitudinal thread passage on the first pick of the shuttle following replenishment.

2. An automatically threading loom shuttle having a longitudinal thread passage and side delivery eye, a scroll in the longitudinal thread passage having its ends secured at opposite sides of the thread passage and provided with a loop extending in a curved path transversely of the thread passage between the ends of the scroll that the thread may be deflected and tensioned by passing over and under the ends of the scroll on the first pick of the shuttle following replenishment.

3. An automatically threading loom shuttle having a longitudinal thread passage and side delivery eye, a scroll having its axis extending longitudinally in the thread passage and its ends secured to the walls of the thread passage at opposite sides of the longitudinal axis thereof to deflect and tension the thread at one side of the longitudinal axis by passing over and under the terminal portions of the scroll on the first pick of the shuttle following replenishment.

4. An automatically threading loom shuttle having a longitudinal thread passage and side delivery eye, a scroll having a loop in the longitudinal passage and provided with two leg portions, one of which adjacent the bobbin chamber is secured to a side wall of the thread passage and the other of which nearer the side delivery eye is secured to the opposite wall of the thread passage that the thread may be deflected over and under the two leg portions of the scroll and tensioned on the first pick of the shuttle following replenishment.

5. An automatically threading loom shut-

tle having a longitudinal thread passage and side delivery eye, a scroll mounted in the thread passage and having its ends secured at opposite sides of the thread passage that the thread may be tensioned between the terminal portions of the scroll on the first pick of the shuttle following replenishment, and tensioning means frontward of the scroll to engage the thread on the second pick of the shuttle following replenishment to maintain substantially uniform tension on the thread during subsequent weaving.

6. An automatically threading loom shuttle having a longitudinal thread passage and side delivery eye, a scroll having its ends secured at opposite sides of the thread passage and provided with a loop extending in a curved path transversely of the thread passage between the ends of the scroll that the thread may be deflected and tensioned on the first pick of the shuttle following replenishment, and means for engaging the thread on the second pick of the shuttle as the thread passes to the side delivery eye to withdraw the thread from the full tensioning effect of the scroll and apply a separate tension to the thread for subsequent weaving.

7. An automatically threading loom shuttle having a longitudinal thread passage and side delivery eye, a scroll in the thread passage to apply tension to the thread on the first pick of the shuttle following replenishment, and a separate tensioning device which engages and tensions the thread only when the thread is delivered from the side delivery eye on the second pick of the shuttle and comprising a member for deflecting the thread from the full tensioning effect of the scroll.

40 8. An automatically threading loom shuttle having a scroll for tensioning the thread on the first pick of the shuttle following replenishment, and a separate thread tensioning device for tensioning the thread on the second and subsequent picks of the shuttle when the thread is delivered from the side delivery eye, including a member at the side of the longitudinal axis of the scroll opposite the side delivery eye for holding the thread from the full tensioning effect of the scroll when the thread is delivered from the side eye during weaving.

9. An automatically threading loom shuttle having a longitudinal thread passage and side delivery eye, means for tensioning the thread on the first pick of the shuttle following replenishment, and separate means to apply tension to the thread on the second and subsequent picks of the shuttle when the thread is delivered from the side delivery eye, including a thread deflector inclined laterally to the side of the thread passage opposite the side delivery eye to deflect the thread from the full tensioning effect of the

means for tensioning the thread on the first pick of the shuttle.

10. An automatically threading loom shuttle having a side delivery eye, a threading block having a longitudinal thread passage and provided with a thread director, a thread tensioning device for placing tension on the thread when it is delivered from the side eye, comprising a thread deflector extending from the thread director backwardly and transversely relative to the longitudinal axis of the thread passage, and a resilient member cooperating with the thread deflector to impart tension to the thread when the thread leads to the side delivery eye.

11. An automatically threading loom shuttle having a side delivery eye, a threading block having a longitudinal thread passage and provided with a thread director, a thread tensioning device for placing tension on the thread when it is delivered from the side eye, comprising a thread deflector extending from the thread director backwardly and transversely relative to the longitudinal axis of the thread passage that the thread may pass about the thread deflector on the second pick of the shuttle following replenishment when it leads through the side eye, and a resilient member for bending the thread relative to the deflector to apply tension during weaving.

12. An automatically threading loom shuttle having a longitudinally extending thread passage and a side delivery eye, a thread director for directing the thread to the side delivery eye on the second pick of the shuttle following replenishment of filling, a thread deflector extending from the thread director diagonally backward and across the longitudinal thread passage to the side thereof remote from the side delivery eye to engage the thread and deflect it towards the side of the thread passage remote from the side delivery eye when the shuttle is fully threaded.

13. An automatically threading loom shuttle having a longitudinal thread passage and a side delivery eye, means in the thread passage to tension the thread on the first pick of the shuttle following replenishment, and a separate tensioning means in the shuttle which engages the thread when the thread is delivered from the side delivery eye on the second pick of the shuttle, said first tensioning means becoming ineffective to tension the thread when the thread is fully threaded in said shuttle.

14. An automatically threading loom shuttle having a longitudinal thread passage and a side delivery eye, thread tensioning mechanism associated therewith and operative to apply tension to the thread during normal running of the shuttle when the shuttle is completely threaded, and additional tensioning means effective to tension the thread during the first pick of the shuttle following replenishment, the thread being deflected from

control of the additional tensioning means in the complete threading of the shuttle.

15. In a self-threading shuttle, a shuttle eye, tension mechanism associated therewith and operative to tension the weft on the second pick of the shuttle after weft replenishment, and additional means to tension the weft during the first pick of said shuttle, said additional means becoming wholly or 10 partially inoperative when the weft is fully threaded in said shuttle.

In testimony whereof, I have signed my name to this specification.

CLARE H. DRAPER.
